UNITED STATES PATENT OFFICE.

AXEL G. GULBRANSEN, OF CHICAGO, ILLINOIS.

AUTOMATIC-PLAYING PIANO.

No. 874,675.

Specification of Letters Patent.

Patented Dec. 24, 1907.

Application filed August 20, 1906. Serial No. 331,230.

To all whom it may concern:

Be it known that I, AXEL G. GULBRANSEN, a citizen of the United States, residing at Chicago, in the county of Cook and State of Illinois, have invented a certain new and useful Improvement in Automatic-Playing Pianos, of which the following is a full, clear, concise, and exact description, reference being had to the accompanying drawings, forming a part 10 of this specification.

My invention relates to mechanical musical instruments and has for its particular object improved construction and arrangement of the primary pneumatic mechanisms therefor.

15 My invention is particularly adaptable where the pneumatic playing attachments are placed inside the instrument casing, and the pneumatic mechanisms of my construction are so compact that the original piano or 20 other instrument casing affords sufficient space, and it is, therefore, unnecessary to enlarge the casing. In mechanisms of this kind the practice has been to provide only one bellows which was connected with the hammer 25 actuating mechanism in some manner, and it was necessary to make the single bellows comparatively long in order that they furnish the necessary strength to give suitable action. These long bellows, however, take up valuable 30 space and besides are not sufficiently quick to respond.

One of the features of my invention lies in dividing the single bellows into a plurality of bellows, arranged one above the other and 35 connected in parallel. Upon connection of the bellows with the low pressure chamber, the parallel bellows are simultaneously and immediately actuated, and they respond immediately to produce the necessary action of 40 the associated striking hammer. The reason for this seems to be that the bellows when arranged in this parallel manner are brought closer to the low pressure chamber and the air is more quickly withdrawn therefrom than 45 if the bellows were arranged serially to form one long bellows.

Another feature of my invention resides in the improved adjustable abutments which are connected with the abstract rods which 50 abutments are engaged by the parallel bellows. The adjustable means on these abutments extend above beyond the pneumatic mechanisms and can be very readily manipulated without in any way disturbing the 55 pneumatic mechanism. I also employ individual means for suspending the primary

valve, and all these various improvements will be better understood by referring to the drawings which accompany this specification.

In these drawings, Figure 1 is an end view 60 of the pneumatic mechanism outfit, arranged within a piano casing; Fig. 2 is a top view of a section of the pneumatic mechanism outfit; Fig. 3 is a rear view of Fig. 1; Fig. 4 is a sectional view taken on line 4—4 of Fig. 2; Fig. 65 5 is a top view of Fig. 4 with the valve block removed; Fig. 6 is an enlarged front view, showing one of the adjustable abutment rods and the method of its adjustment on the abstract rod; Fig. 7 is a sectional view taken 70 on line 7—7 of Fig. 6.

The low pressure chamber (a) is rectangular and extends lengthwise along the front of the piano to the rear of the fall board (b) of the piano structure, and this chamber is 75 formed by the rear wall 3, a top wall 4, a lower wall 5 and the front wall or cover 6, this cover being hinged at its lower end as shown, and provided with locking means 7 at the top, such as a hook, whereby upon removal of the fall board, the cover may be 80 opened to reveal the interior of the air chamber. The air chamber (a) is connected with exhaust bellows in any manner, which exhaust bellows connect with feeder bellows, 85 suitably arranged to be operated by pedal mechanism in any well known manner.

The construction and suspension of each pneumatic mechanism is illustrated in Fig. 4. Each mechanism comprises a body wall or 90 mounting block 8, below which are situated two or more bellows 9¹, 9², and so on. The movable part 10 of the bellows 9¹ is hinged at its front end to the underside of block 8. The top wall 11 of the bellows 9² is secured at 95 its rear end to the rear end of block 8, and its movable wall 12 is hinged with the rear end of the top wall 11. These bellows are arranged one above the other, the movable wall 10 of the upper bellows having a bifurcated extension 13 while the movable wall 12 of the lowermost bellows has an extension 14 having a bearing opening 15. A connecting rod 16 pivots at its upper end on a pin 17 which passes through the bifurcated extension 13, while the lower end of the connecting rod pivots on a pin 18, extending through the bearing opening 15. Over the edge of the extension 14 is secured the pad 19 of felt or other soft material, and this pad engages an 110 abutment 20 secured to a corresponding abstract rod in a manner which will be pres-

ently described. The weights of the lower walls of the bellows are sufficient to normally distend the bellows, and upon collapse of the bellows when the air is withdrawn therefrom, 5 their force is collected and transmitted through the connecting rods to the extension 14 whereupon the engaged abutment is raised and the connecting abstract rod actuated to cause operation of the associated 10 hammer mechanism.

In the front end of the block 8 is a cylindrical chamber 21 having an annular shoulder 22 about the edge of which is glued the valve diaphragm 23 and supporting at its 15 center a small disk or pad 24. This diaphragm divides the chamber 21 into an upper section 21^u and a lower section 21^l, and secured to the top of block 8 over the chamber 21 is a valve block 25, having a cylindrical chamber or opening 26 concentric with the chamber 22. Within this chamber 26 is a cylindrical valve 27, through which extends a vertical valve stem 27' which may be of wood or a wood screw as shown. The 20 lower end of this stem is normally a slight distance above the pad 24 on the diaphragm 23. This valve normally closes opening 28 through the lower wall of the chamber 26, and communicating with chamber 21^u. 25 Over the mouth of the chamber 26 is glued a leather plate 29, having a central opening 30 which communicates with atmosphere. Secured to the top of the valve 27 is a thin disk 31 of leather, having radial extensions 30 or straps 32 which at their ends are glued over the edges about the chamber 26 as shown in Fig. 4 and Fig. 2. The valve is thus confined and guided within this chamber but may very readily and without the 35 least resistance be moved up or down. The chamber 26 communicates with the interior of the upper bellows 9¹ through a passageway 33, while this chamber communicates with the interior of the lower bellows 9² 40 through a passageway 34.

Figs. 2 and 3 show the compact arrangement of the pneumatic mechanisms which are arranged in three rows as shown, each 45 row being offset so that the planes of the projections 14 are equally spaced and in accordance with the abstract rods to be engaged thereby. Each pneumatic mechanism is secured at its front end to the rear wall 3 of the air chamber by means of screws 50 35 as best shown in Fig. 4. The chamber 21^u connects with the low pressure chamber (a) through a comparatively large passageway 36, while the chamber 21^l connects with the chamber (a) through a smaller passageway 37. This connection of the lower chamber 21^l with the low pressure chamber (a) 55 is further gaged by a washer or disk 38, having the pin hole opening or perforation 39. The passageway 37 also communicates with 60 the passageway 40 which is connected with

one of the openings in the tracker board. Normally, therefore, both the upper and lower diaphragm chambers are connected with the low pressure supply chamber, and the diaphragm will, therefore, be in its lower 70 position and the valve 27 which is subjected to atmospheric pressure is forced down to close the opening 28. As the music sheet passes over the tracker board, the passageways 40 are connected with atmosphere. 75 This atmospheric air immediately rushes into the lower diaphragm chamber through the passageway 37, and the diaphragm is thrown upwardly, the pad 24 striking the lower end of the valve stem 27, and the valve 80 27 is forced upwardly to expose the opening 28 and to close the outlet 30 to atmosphere. The bellows are, therefore, in communication with the upper diaphragm chamber which is connected with the low pressure reservoir, 85 and these bellows are immediately and simultaneously collapsed to raise the engaged abstract rod. The pin hole opening 39 being very small, practically the entire force of atmospheric air is expended in throwing up the diaphragm. When the passageway 40 is again closed to atmosphere, the pressure in the upper and lower diaphragm chambers will be reduced and equalized. 90 As these bellows are arranged in parallel as 95 described and situated close to the low pressure reservoir, the air can be quickly withdrawn therefrom, and collapse thereof is almost instantaneous, thus insuring quick response and action. 100

The diaphragm and valve stem, as has been already stated, are normally out of engagement, and this allows expansion, contraction or other distortion of the diaphragm without destroying the adjustment, but 105 when the corresponding passageway 40 connects with atmosphere and the diaphragm is suddenly thrown up, the valve stem will be struck and the valve actuated. This striking connection between the diaphragm and 110 stem insures quicker and stronger action of the valve, as the diaphragm may gain suitable momentum before striking the stem.

It is very desirable that the abutments 20 be adjustable without its being necessary to 115 in any way disturb the pneumatic mechanisms. Each abutment 20, therefore, is secured to the lower end of an adjusting rod 41, having upper and lower slots 42 and 43, through which pass screws 44 and 45. These 120 screws engage the abstract rods, and the lower screws are drawn in just sufficiently to hold the abutment rod against the abstract and to guide it upon vertical movement thereof. The upper screws are all in the 125 same horizontal line which is above the pneumatic mechanism outfit, and to adjust the various abutments the fall board of the piano is removed, and by means of a screw driver or other instrument, the upper screws 130

- may be loosened and the abutment rods raised or lowered to proper adjustment, whereupon the screws are again tightened. The front wall 6 of the low pressure reservoir or chamber may also be swung downwardly on account of its hinged connection to give access to the screws 35 supporting the pneumatic mechanisms and the washers 38. By merely withdrawing the screws 35 which 10 normally hold the pneumatic mechanism in place, this pneumatic mechanism may be removed, and being a unitary structure, there will be absolutely no displacement or disarrangement of the parts thereof and 15 their adjustment, and the pneumatic mechanisms can be thus very easily inspected and the mechanisms repaired and adjusted without the necessity of doing this in a confined place.
- 20 By means of the various features of my invention, a very compact and a very effective pneumatic mechanism is provided which is very simple of construction and whose operation and response is extremely efficient.
- 25 I realize that changes may readily be made in the construction and arrangement of the parts which would still be within the claims which are hereto appended and which I desire to secure by Letters Patent.
- 30 1. In an automatic playing instrument, the combination with a piano having abstract rods, of automatic playing mechanism, a plurality of pneumatic action mechanisms for the automatic playing mechanism in the 35 form of units, each unit comprising a plurality of bellows arranged in a tier, a common mounting block from which the bellows are supported, and primary valve mechanism in the block for simultaneously controlling the bellows to cause cumulative operation thereof, the movable parts of each set of bellows being connected with one of the piano abstract rods.
2. In pneumatic action mechanism for 45 mechanically operated pianos, the combination with a common mounting block, of a plurality of bellows supported below the mounting block, a common primary valve mechanism for the bellows arranged in the 50 mounting block, said mounting block, bellows and valve mechanism comprising an individual unitary structure, the movable members of the bellows being connected together and adapted for connection with key 55 operating mechanism of the piano.
3. In an automatic playing piano the combination with the abstract rods and the hammer actuating mechanism of the piano, of a plurality of individual action mechanism units one for each of the abstract rods, a plurality of bellows for each unit having their movable members connected together and adapted for connection with the corresponding abstract rod, a common mounting 60 block from which the bellows are supported, a common primary valve mechanism arranged in the mounting block and connected through suitable channels with the bellows, and a flat rectangular wind chest extending across the piano in front of the ends of the abstract rods, said pneumatic action units being removably supported from the rear wall of the wind chest, said bellows acting cumulatively and their combined force upon operation causing movement of the abstract 70 rod and the hammer mechanism connected therewith.
4. A pneumatic action mechanism unit for mechanically operated pianos comprising a common mounting block 8, a plurality of bellows arranged in a vertical tier below said mounting block and supported therefrom, links 16 connecting together the movable members of the bellows at the exterior thereof, a shelf 19 on one of the bellows 80 adapted for association with hammer actuating mechanism of the piano, primary valve mechanism mounted in the block 8 and common to all the bellows, operation of the valve mechanism causing cumulative operation of 85 the bellows.
5. In an automatic playing instrument comprising an upright piano and automatic playing mechanism, the combination with vertical, abstract rods for the piano, of a wind chest for the automatic playing mechanism extending along the interior of the piano in front of the lower ends of the abstract rods, a plurality of pneumatic action mechanisms for the automatic playing 95 mechanism in the form of units, each unit comprising a plurality of bellows arranged in a tier, a common mounting block for each unit from which the bellows are supported, a primary valve mechanism in each mounting 100 block for simultaneously controlling the bellows to cause cumulative operation thereof, said units being supported in rows from the rear wall of the wind chest, and the movable parts of each set of bellows being connected 105 with one of the abstract rods.
6. In a mechanically-operated piano, the combination with the piano action having vertical abstract rods, of a plurality of pneumatic action mechanisms supported in vertical and horizontal rows directly in front of the lower ends of the abstract rods, an attachment for each abstract rod having connection with one of the pneumatic action mechanisms so that actuation of the pneumatic action mechanism will be transmitted through the attachment to the corresponding abstract rod, means for guiding the lower end of each attachment, and adjustable means for guiding and securing the upper 115 end of each attachment to the abstract rod, said attachments being adapted for vertical movement whereby their position with respect to the pneumatic action mechanisms 120 may be adjusted, the upper guiding and se- 130

curing means being all disposed in a line which is above and clear of the pneumatic action mechanism whereby each attachment may be vertically adjusted and secured to 5 the abstract rod after adjustment without disturbing or moving the pneumatic action mechanisms.

7. In a mechanically-operated piano, the combination with the piano action having 10 abstract rods, of a pneumatic action mechanism associated with each abstract rod, said pneumatic action mechanisms being disposed in vertical and horizontal rows directly in front of the lower end of the abstract rods, an abutment plate for each abstract rod having connection at its lower end with the corresponding pneumatic action mechanism, an elongated slot through the lower end of each abutment plate, a screw 20 engaging through said slot and with the abstract rod to confine the plate to the abstract

rod but to allow vertical movement thereof, another slot through the upper end of each abutment plate, and a second screw engaging through the upper slot and with the abstract rod, each abutment plate being adapted for vertical movement when the upper screw is sufficiently loose and the plate being secured to the abstract rod when the upper screw is drawn tight, the upper screws being 25 all in a line above the pneumatic action mechanisms so that adjustment of each abutment plate with reference to its associated pneumatic action mechanism may be accomplished without moving or disturbing 30 any of the primary action mechanisms.

In witness whereof, I hereunto subscribe my name this 18th day of August, A. D. 1906.

AXEL G. GULBRANSEN.
